VERNIER CONDENSER

De Witt Rugg Goddard, Riverhead, N. Y., assignor
to Radio Corporation of America, a corporation
of Delaware

Application May 25, 1939, Serial No. 275,692

5 Claims. (Cl. 175—41.5)

This invention relates to a new and useful vernier condenser which is particularly adapted for use with a radio receiver.

An object of this invention is to simplify and improve vernier condensers having a small range of capacity.

Another object of this invention is to provide a small compact vernier condenser unit having two ranges of capacity variation.

In the prior art, whenever it was desirable to obtain very small ranges of vernier action on the main tuning condenser of a receiver, it was customary to use two vernier condensers, for example, one having a capacity variation range in the order of one percent of the main condenser and the other having a capacity variation range roughly in the order of $\frac{1}{100}$ of one percent of the main tuning condenser. Such additional vernier condensers naturally add complication to the receiver, increase the cost and frequently require crowding of various component receiver parts. The vernier condenser of my invention does away with the necessity of requiring two vernier condensers in the radio receiver for the reason that the single condenser provides two ranges of capacity variation, the two ranges being obtained by merely moving the position of the condenser operating knob.

This invention will best be understood by referring to the accompanying drawing, in which:

Fig. 1 is an elevation of the condenser looking from the rear; and

Fig. 2 is a longitudinal section of Fig. 1.

Referring now in detail to the drawing, it will be seen that the stationary semi-circular condenser plate 1 is capacitively acted upon by a movable semi-circular condenser plate 2 to obtain the necessary large capacity variations. Stationary plate 1 is mounted upon an insulating base 3 by means of an angle strip member 4. Movable plate 2 is secured to a metal shaft 5 by means of a collar 6 and a set screw 7. A circular movable plate 8 is likewise secured to shaft 5 by means of collar 9 and set screw 10. An upright or panel 11 supports a large bushing or shaft bearing 12, which is secured to member 11 by means of nut 13. The metal shaft 5 on which is secured movable plate 2 and circular plate 8 has two annular grooves or rings machined as indicated at 15 and 16. Shaft bushing 12 has an aperture 17 in which is located a spherical ball-shaped member 18. A spiral spring 19 normally keeps the shaft 5, by means of frictional engagement with ball 18, from moving horizontally through the bushing and yet allows it to

be rotated for obtaining the necessary capacity variation. However, a sharp forward pull on knob 20 will move the shaft through bushing 12 until the ball drops into groove 16, thereby locating the condenser shaft and movable plates 2 and 8 in a new position. This new position, which is indicated by dotted lines, provides a much greater clearance or plate spacing between the movable and stationary plates, thereby giving a much smaller range of capacity variation.

This arrangement provides two ranges of capacity for the vernier condenser. However, by the addition of the circular plate 8 there is provided an arrangement whereby the total capacity of the condenser at its mid-scale position does not change appreciably. It will be noted that movable plate 8 is so situated and its spacing and capacitive area proportioned that when shaft 5 is pulled out the condenser knob being set at the mid-scale, its approach to stationary condenser plate 1 adds a fixed value of capacity which just compensates for the decrease in capacity due to the increased spacing between the movable condenser plate 2 and the stationary plate 1. Due to the fact that plate 8 is circular in shape, it contributes no change in capacity upon the rotation of shaft 5. An advantage of this type of condenser is that it is possible to calibrate or engrave on the dial two separate frequency scales, one applying when groove 15 engages ball 18, the other when groove 16 engages the ball. Then, when the condenser is operated with greater frequency range, i. e. groove 15 engaging ball 18, one need only to note whether the frequency to which the dial is set is a frequency lying in the range of the other calibration scale, in order to determine whether the particular frequency can be tuned in with the dial in the narrow range position, i. e. groove 16 engaging ball 18.

Although only one modification of this invention is disclosed, it is distinctly understood that it should not be limited in the general scope thereof.

What I claim is:

1. A vernier condenser having two ranges of capacity variation comprising a fixed non-circular electrode, a rotatable shaft, two movable plates mounted on said shaft, one of said movable plates being circular and the other non-circular, the relative areas of each one of said plates and the distance between said plates and their position with respect to said fixed electrode being so chosen that the total capacity between said plates

and said fixed electrode is the same in both ranges of capacity variation of the condenser in its mid-position of rotation, said fixed electrode located intermediate said movable plates to be in capacitive engagement therewith, means to change the capacity range by changing the spaced relationship between said plates and said fixed electrode to give a different range of capacity.

2. A variable condenser having two ranges of capacity variation comprising a semi-circular fixed electrode and a movable semi-circular plate, a circular movable plate, a shaft for rotating said movable plates, said shaft having a pair of annular grooves located thereon, the relative areas of each one of said plates and the distance between said plates and their position with respect to said fixed electrode being so chosen that the total capacity between said plates and said fixed electrode is the same in both ranges of capacity variation of said condenser in its mid-position of rotation, said fixed semi-circular electrode positioned for capacitive engagement between said movable semi-circular plate and said circular plate, and means adjacent said shaft for engaging said annular grooves whereby said shaft is positioned to change the space relationship between said fixed electrode and both movable plates and thus change the capacity range of the condenser.

3. A variable condenser having a first and a second capacity range comprising a fixed non-circular electrode, a movable non-circular plate, a shaft for rotating said movable non-circular plate, a pair of annular grooves located on said shaft, a circular plate also located on said shaft, the relative areas of each one of said plates and the distance between said plates and their position with respect to said fixed electrode being so chosen that the total capacity between said plates and said fixed electrode is the same in both ranges of capacity variation of said condenser in its mid-position of rotation, said fixed non-circular electrode positioned for capacitive engagement between said non-circular plate and said circular plate, and means adjacent said shaft for engaging said annular grooves whereby the shaft is positioned to change the space relationship between said fixed electrode and both movable

plates and thus change the capacity range of the condenser.

4. A variable electric condenser having two alternative ranges of capacitive variation with equal capacity in each range at a predetermined setting of said variation, said condenser comprising, a non-circular fixed electrode, a rotatable shaft, a circular plate located on said shaft and arranged on one side of said fixed electrode, a non-circular plate located on said shaft and positioned on the other side of said fixed electrode, means on said shaft to provide two alternative positions of said plates with respect to said fixed electrode to give a small and large range of capacitive variation, means for axially shifting said shaft between said alternative operative positions as determined by said first mentioned means, the relative areas of each one of said plates and the distance between said plates and their position with respect to said fixed electrode being so chosen that the total capacity between said plates and said fixed electrode is the same in both alternative operative positions when said condenser is set at the predetermined setting of variation.
5. A variable condenser having a first and a second range of capacity variation comprising a fixed non-circular electrode, a movable non-circular plate, a shaft for rotating said movable non-circular plate, a circular plate also located on said shaft, said fixed non-circular electrode positioned for capacitive engagement between said non-circular movable plate and said circular plate, the relative areas of each one of said plates and the distance between said plates and their position with respect to said fixed electrode being so chosen that the capacity between said plates and said fixed electrode is the same in both ranges of capacity variation of said condenser in its mid-position of rotation, a bushing surrounding said shaft, a spherical-shaped member having spring tension means located within said bushing, said shaft having a pair of annular grooves which are located so as to cooperate with said spherical-shaped member to maintain the space relationship between said fixed electrode and movable plates and thus change the capacity range of the condenser from one range to another.

DE WITT RUGG GODDARD.
